PERCUSSION TOOL FOR WELLS

Ross Bassinger, Houston, Tex.

Application February 2, 1948, Serial No. 5,855

3 Claims. (Cl. 255—4.4)

1

This invention relates to new and useful improvements in percussion tools for wells.

The invention represents in many respects an improvement over my co-pending application, Serial No. 686,497, filed July 26, 1946, now Patent No. 2,507,585 issued May 16, 1950.

It has been a wide-spread occurrence in the drilling industry, that in drilling wells in certain localities or fields, very hard and rocky formations are sometimes encountered which are very difficult to drill, resulting in uncommonly high drilling expenses, and at the same time, very slow progress in drilling operations. The usual rock type bits have not proved effective on these formations, as little as one foot of hole drilled before it is necessary to pull the tubing and replace the bit being a fairly common occurrence. Obviously, such conditions greatly delay the completion of a well with the corresponding increase in expenses, as well as creating highly undesirable collateral conditions which are not favorable to the driller.

Heretofore, various percussion type bits have been developed and tried in drilling operations. At the present time, none of these bits have proved successful or answered the need for a drilling assembly capable of efficient operation under the unfavorable conditions usually encountered, or even under favorable conditions. In some instances, attempts have been made to use a cable tool type bit, but necessarily, such operations were not satisfactory after a certain depth of hole had been obtained.

It is therefore, one object of this invention to provide an improved percussion tool adaptable for use with a drill bit, which is effective and operative under normal conditions within a well bore, to deliver a series of hard blows to a drill bit, or to other suitable tools and connections within a drill string.

It is an important object of the invention to provide an improved percussion tool for use in wells, which is responsive to flow of the drilling fluid through a well conductor to deliver intermittent blows of considerable magnitude and force to a drill bit, or other connection in the drilling string.

A further object of the invention is to provide an improved percussion tool having a hammer which is given momentum by the flow of the drilling fluid and with which blows of considerable intensity and magnitude may be delivered to a suitable connection in a drilling string.

Still another object of the invention is to provide an improved percussion tool for use in wells

wherein the upper end of a hammer is adapted to be acted upon by the flow and pressure of the drilling fluid to impart a downward impetus to the hammer, and wherein means are provided coacting with the upper end of the hammer to react also to the drilling fluid and move downwardly as does the hammer, said latter means being stopped and returned to its upward position before the hammer has completed its downward travel under the momentum imparted thereto, so as to receive the upper end of the hammer upon the return of the latter to its upward position and to commence a subsequent downward travel of said hammer, whereby intermittent blows of considerable intensity are delivered by the hammer to a drill bit or other suitable means.

Yet another object of the invention is to provide an improved percussion tool of the character described wherein the portion of the hammer acted upon by the pressure of the drilling fluid may rotate with respect to the hammer while being prevented from undergoing longitudinal movement with respect thereto.

Still another object of the invention is to provide an improved percussion tool of the character described wherein a dash-pot structure is provided for the means coacting with the upper portion of the hammer in reaction to the drilling fluid, said dash-pot means reducing the mechanical shock imparted to the coacting means as the latter moves upwardly and downwardly within the percussion tool.

Another object of the invention is to provide an improved percussion tool having a hammer adapted to react to the flow and pressure of drilling fluid to deliver a series of impact blows wherein the hammer suspended within the tool from a tension type spring or other type of resilient or tension exerting element.

Yet another object of the invention is to provide an improved percussion tool of the type described having a control sleeve which coacts with the hammer to cause the latter to reciprocate, wherein the control sleeve is suspended within the tool by a plurality of tension type springs.

A particular object of the invention is to provide an improved method of drilling wells wherein blows of considerable magnitude are imparted to a rock type bit or a roller bit while said bits are being rotated so that substantially all of the advantages flowing from the use of roller bits are realized in addition to those advantages resultant from percussion drilling.

10 5 10 15 20 15 20 25 30 35 40 45 50

wherein the upper end of a hammer is adapted to be acted upon by the flow and pressure of the drilling fluid to impart a downward impetus to the hammer, and wherein means are provided coacting with the upper end of the hammer to react also to the drilling fluid and move downwardly as does the hammer, said latter means being stopped and returned to its upward position before the hammer has completed its downward travel under the momentum imparted thereto, so as to receive the upper end of the hammer upon the return of the latter to its upward position and to commence a subsequent downward travel of said hammer, whereby intermittent blows of considerable intensity are delivered by the hammer to a drill bit or other suitable means.

Yet another object of the invention is to provide an improved percussion tool of the character described wherein the portion of the hammer acted upon by the pressure of the drilling fluid may rotate with respect to the hammer while being prevented from undergoing longitudinal movement with respect thereto.

Still another object of the invention is to provide an improved percussion tool of the character described wherein a dash-pot structure is provided for the means coacting with the upper portion of the hammer in reaction to the drilling fluid, said dash-pot means reducing the mechanical shock imparted to the coacting means as the latter moves upwardly and downwardly within the percussion tool.

Another object of the invention is to provide an improved percussion tool having a hammer adapted to react to the flow and pressure of drilling fluid to deliver a series of impact blows wherein the hammer suspended within the tool from a tension type spring or other type of resilient or tension exerting element.

Yet another object of the invention is to provide an improved percussion tool of the type described having a control sleeve which coacts with the hammer to cause the latter to reciprocate, wherein the control sleeve is suspended within the tool by a plurality of tension type springs.

A particular object of the invention is to provide an improved method of drilling wells wherein blows of considerable magnitude are imparted to a rock type bit or a roller bit while said bits are being rotated so that substantially all of the advantages flowing from the use of roller bits are realized in addition to those advantages resultant from percussion drilling.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a longitudinal sectional view of the upper portion of a percussion tool constructed in accordance with this invention,

Fig. 2 is a continuation of Fig. 1 and showing the next lower portion of the tool,

Fig. 3 is a continuation of Fig. 2 and illustrating the next lower portion of the tool,

Fig. 4 is a continuation of Fig. 3 and showing the lower end of the tool,

Figs. 5 through 9 are horizontal, cross-sectional views taken on the corresponding lines of Figs. 1 through 4,

Fig. 10 is a longitudinal, sectional view of a percussion tool constructed in accordance with a modification of this invention,

Fig. 11 is a continuation of Fig. 10, with its lower end broken away, and illustrating the next lower section of the modified form of the invention, and

Figs. 12 through 16 are horizontal, cross-sectional views taken on the corresponding lines of Figs. 10 and 11.

In the drawings, the numeral 10 designates the uppermost section of the tubular housing within which the percussion tool is contained. The section 10 carries a reduced, upwardly extending, screw-threaded pin 11 upon its upper end for connecting the device to a suitable drilling string, and the pin is provided with an axial bore 12 to which drilling fluid or mud may pass to the interior of the section 10. The lower end of the section is provided with tapered, internal screw-threads 13 which receive the screw-threaded upper end of the next lower housing section 14. Because of the tapered structure of the threads 13, the inside and outside walls of the sections 10 and 14 are substantially continuous and no loss of internal diameter or excessive increase of outside diameter of the housing results.

A spider 15 is disposed within the lower portion of the section 10 and carries an annular marginal collar 16 which rests upon an internal, annular shoulder 17 formed in the upper portion of the section 14. The spider 15 is thus held against downward movement with respect to the housing. The spider is provided with a plurality of radially extending webs 18 which are connected between the collar 16 and a central, vertical sleeve 19. The upper end of an eye bolt 20 extends through the sleeve 19 and receives a suitable nut 21 above said sleeve so as to limit downward movement of the bolt with respect to the spider. An elongate coiled spring 22 or other type of resilient or tension-exerting element depends from the eye of the bolt 20 and extends downwardly through the bore of the section 14. The spring 22 is relatively heavy and large in diameter so as to be capable of carrying considerable loads yet to undergo the desired elongation when such are applied.

The housing 14 extends below the lowermost point of expansion of the spring 22 and is provided with internal, tapered screw-threads 23 which receive the screw-threaded pin 24 of a connecting nipple 25. The nipple 25 is of relatively heavy walled construction but has an out-

side diameter substantially equal to the outside diameter of the sections 10 and 14. A reduced screw-threaded pin 26 is provided upon the lower end of the nipple 25 and receives the upper end of a third housing section 27 similar to the section 14. A reduced-diameter, depending skirt 28 is formed upon the lower extremity of the pin 26 and projects downwardly into the interior of the housing section 27. Radial ports 29 are cut in the upper portion of the skirt 28 so as to permit drilling fluid to enter the annular space 30 between said skirt and the inner wall of the section 27.

A second nipple 31 is secured to the lower end of the section 27 by a screw-threaded joint 32, said nipple having a reduced-diameter sleeve 33 of considerable length extending upwardly into the interior of the section 27 to a point spaced a short distance below the lower edge of the skirt 28. The sleeve 33 is provided with a smooth axial bore 34 within which an elongate control sleeve 35 has a snug sliding fit. The upper edge or end of the sleeve 33 is rounded as shown at 36, and the upper end of the control sleeve 35 is enlarged to form an integral, external, annular ring or flange 37 about said upper end of the control sleeve. The ring 37 carries an annular groove 38 in its underside, the groove being semi-circular in cross-section so as to receive the rounded upper end 36 of the sleeve 33. A collar 38 encircles the upper portion of the sleeve 33, the latter having a sliding fit within the bore of the collar which abuts the underside of the ring 37. The collar is provided with an upstanding marginal lip 39 which fits snugly within a complementary marginal recess 40 provided on the underside of said ring 37.

A suitable compression spring 41 of the coiled type is confined between the lower edge of the collar 38 and the upper end of the nipple 31, said spring encircling in a relatively snug fashion the outer periphery of the sleeve 33. Thus, the spring serves to urge the collar 38 and therefore the control sleeve 35 upwardly with respect to the sleeve 33 so as to cause the ring 37 to abut the bottom edge of the skirt 28. The control sleeve is free to undergo reciprocal movements within the bore 34, but the spring 41 constantly urges said sleeve upwardly within said bore.

A lower housing section 42 is screw-threadedly connected to the lower end of the nipple 31 and carries an elongate hammer 43 of considerable mass. A cylindrical recess 44 is formed in the center of the upper end of the hammer and receives the enlarged lower end 45 of an elongate cylindrical control piston 46. Chordal bores 47 are cut in the upper end of the hammer and the enlarged portion 45 of the control pistons, said bores being so disposed as to have their center axes tangential to the cylindrical side wall of said enlarged portion 45. Suitable pins 48 are positioned within the bores 47 and by engaging partially within the upper end of the hammer and partially within the enlarged section 45 lock the two elements together and prevent their longitudinal separation. If desired, that portion of the bores 47 which is formed within the enlarged lower end 45 of the control piston may be in the nature of an annular groove 47', semi-circular in cross-section and extending circumferentially of the portion 45 at this point. Such a structure would permit rotation of the portion 45 within the recess 44 while retaining a secure fastening action. An annular groove 49 is cut in the wall 70 of the recess 44 adjacent the lower end thereof

and receives a distortable packing ring 50 having a circular cross-section. The ring 50 may be formed of synthetic rubber or any other suitable material and serves to pack off the space between the portion 45 of the control piston and the inner wall of the recess 44.

The control piston 46 is of such an outside diameter as to have a snug sliding fit within the bore 52 of the control sleeve 35. If desired, the lower end of the control sleeve and the upper end of the piston may be chamfered so as to permit the ready entry of the piston into the sleeve.

For the purpose of suspending the hammer 43 within the section 42, an elongate, flexible metallic cable 53 is provided with an eye 54 and a thimble 55 at its upper end which receive the lower end of the spring 22. The cable 53 extends axially downwardly through the bores of the section 14, the nipple 24, the section 21, and the control sleeve 35, into an axial bore 56 provided in the control piston 46. The bore 56 extends entirely through the control piston 46 and the enlarged portion 45 on the lower end thereof, the lower portion of said bore being enlarged within the portion 45 to form a cable socket 57. That portion of the cable which extends into the socket 57 may be spread and secured therein by the addition of molten metal in the usual fashion. In this manner, the control piston and the hammer are suspended by means of the cable from the spring 22 so that the latter constantly urges the hammer upwardly within the housing section 42.

The hammer 42 is of solid cylindrical construction and has an outside diameter less than the inside diameter of the housing section 42 so that an annular flow space 58 is provided for the passage of drilling fluid. Near its upper end, the hammer carries radially extending, longitudinal guide ribs 59 which bear against the inner periphery of the section 42 and center the hammer within said section while guiding said hammer in its longitudinal movement within the section. The flutes 60 between adjacent ribs 59 are deepened so as to extend into the body of the hammer to provide additional flow space for drilling fluid between said ribs. Similar guide ribs 61 are provided at a point near the lower end of the hammer and cooperate with the guide ribs 59 to maintain the entire length of the hammer substantially centered within the bore of the section 42 while permitting the hammer to undergo longitudinal movement therewithin. Because the flow of drilling fluid between the ribs 61 is reduced, it is not necessary to deepen the flutes between said ribs by cutting them into the body of the hammer.

An enlarged striking head 62 is formed upon the lower extremity of the hammer and an axial bore 63 extends upwardly through said head into the body of the hammer, said bore terminating at a point spaced above the lower guide ribs 61. Above said guide ribs, the hammer is provided with a plurality of radial ports 64 extending outwardly from the bore 63 and communicating between said bore and the annular space exterior of the hammer. Thus, drilling fluid passing downwardly through the annular space 58 may enter into the ports 64 and pass downwardly through the bore 63 to the lower portion of the tool. At the same time, the guide ribs 61 permit a certain portion of the drilling fluid to pass downwardly exteriorly of the hammer and keep the annular space between the lower end of the hammer and the housing section 42 clear of for-

ign matter while also preventing the trapping of fluid within said space.

Internal screw-threads 65 are formed at the extreme lower end of the lower housing section 42 to receive the screw-threaded pin 66 of a retaining collar 67. A tubular sleeve 68 extends upwardly from the pin 66 and has a snug fit within the lower portion of the housing section 42. A bit carrier 69 is disposed at the lower end of the section 42 within the collar 67 and is provided with a reduced, tapered, screw-threaded pin 70 at its lower end. A tubular shank 71 extends upwardly from the bit carrier and is provided with an axial bore 72 vertically aligned with the bore 63. The upper end of the shank forms an anvil 73 upon which the hammer 42 is adapted to strike. Radial ports 74 are provided in the side walls of the shank near the upper end thereof to permit the circulation of drilling fluid between said shank and the inner periphery of the section 42. A plurality of radially extending splines 75 are formed upon the exterior of the bit carrier and engage within complementary grooves 76 extending longitudinally of the interior of the retaining collar 67. The splines permit the bit carrier to undergo longitudinal movement with respect to the retaining collar, but present rotative movement between the two elements. The splines 75 are less in length than the grooves 76 so as to permit said movement. However, the grooves terminate short of the bottom of the retaining collar 67 so as to provide shoulders 77 which receive the splines 75 and limit the downward travel of the said carrier with respect to the collar 67.

A bit 78, which may be of any desirable type has its screw-threaded box 79 engaged by the pin 70, whereby the bit is rigidly secured to the bit carrier 69. The bit is provided with the usual drilling fluid passages 80 which communicate with the bore 72 and permit the flow of drilling fluid.

A pressure responsive type packing ring 81 is recessed in the outer wall of the shank 71 and engages the inner periphery of the upstanding sleeve 68. This packing ring serves to prevent the flow of drilling fluid downwardly between the shank and the retaining collar 67, any drilling fluid which reaches this point of the tool being thereby forced to pass through the radial ports 74.

In the operation of this device, the entire assembly is lowered into the well bore upon the usual drilling string (not shown) until the bottom of the hole is reached. A certain amount of weight upon the bit is desirable to allow the splines 75 to ride downwardly within the grooves 76 and eliminate any direct connection between the tubing string and the bit assembly. The lower end of the retaining collar 67 rests upon the enlarged upper end of the bit, or is elevated slightly thereabove so as to protect the splines 75 against the impact blow delivered by the hammer 42. Upon starting the mud pump (not shown), drilling fluid or mud is circulated downwardly through the drilling string under pressure and passes through the bores of the sections 10 and 14 into the interior of the control sleeve 35. The drilling fluid may also flow through the ports 29 to insure ample circulation about the spring 41 and within the annular space between the sleeve 33 and the housing section 27.

Prior to the starting of the circulation of drilling fluid, the spring 41 will maintain the control sleeve pressed against the lower end of the skirt

28. At the same time, the spring 22 will hold the control piston 46 and the hammer 42 in their upper position wherein said piston telescopes the lower end of the control sleeve 35.

The pressure under which the drilling fluid is pumped through the tubing is dependent upon the particular well or field and may vary considerably. Usually, the deeper the well, the higher the pumping pressure used, values as high as 2,000 pounds per square inch or higher, sometimes being used. About 250 to 300 pounds per square inch pressure is required to operate the present percussion tool. This, of course, is pressure at the tool itself. Therefore, the pumping pressure already being used may be sufficient or an increase in pressure of 200 to 300 pounds may be required to operate the tool.

The pressure at the tool, which may be anything from several hundred pounds to a thousand or so pounds per square inch, acts upon upper end of the piston 46 and also upon the control sleeve 35. Since the spring 41 is not as strong or stiff as the spring 22, the control sleeve is forced downwardly compressing the spring 41. Due to the pressure of the drilling fluid, this downward movement is very rapid and occurs very quickly. The control sleeve travels downwardly until the upper end of the sleeve 33 seats within the groove 38. It is pointed out that the enclosing of the upper end of the sleeve 33 between the sleeve 35 and the collar 38 affords a sizable dash-pot action which eliminates to a considerable extent the shock delivered to the control sleeve when seating upon the upper end of the sleeve 33 under the influence of the relatively high pressure of the drilling fluid. Upon seating of the control sleeve, further downward movement of the latter is prevented.

The downward movement of the control sleeve relieves to some extent the pressure of the drilling fluid acting upon the piston 46, and diverts the flow of the fluid therefrom. However, as soon as the sleeve reaches the bottom of its stroke, the full pressure of the drilling fluid as well as the impact resultant from its momentum is directed upon the piston, thereby forcing the piston and hammer downwardly with great rapidity so as to impart considerable velocity and momentum to the hammer while overcoming the force exerted by the spring 22. The weight of the entire column of drilling fluid within the tubing string is behind this impact, so that there is no hesitation in the flow of the drilling fluid, the force brought to bear on the hammer being sufficient to eliminate any delay in its downward movement.

As the hammer moves downwardly, the piston is withdrawn from the bore 52 of the control sleeve. When this occurs, the drilling fluid is permitted to flow through the bore into the lower part of the tool, while the hammer continues its downward travel under momentum until the lower end of the hammer strikes the anvil 73 and delivers a blow thereto, which is transmitted through the bit carrier 69 to the bit 78. As soon as this blow is delivered, and the momentum of the hammer is dissipated, the spring 22 is free to return the hammer to its upper position.

The piston is withdrawn from the bore 52 before the hammer strikes the anvil. Otherwise, a fluid lock would occur, and the operation of the device would be impaired if not terminated altogether. However, the time interval or the distance traveled by the hammer after such withdrawal is very small, so that the hammer deliv-

ers this blow at substantially peak momentum and velocity. By varying the spacing of the elements so as to change this time interval, the frequency and magnitude of the blows struck may be controlled.

It is not necessary that the piston have a close fit within the control sleeve and a certain degree of by-passing of the drilling fluid between these elements will not substantially impair the operation of the tool. Nor is it necessary that the control sleeve reach the lower end of its stroke before the hammer starts to move downwardly. As the spring 41 is compressed, the back pressure on the piston increases, and the critical value necessary to start downward movement of the hammer may be reached well before the sleeve nears the bottom of its stroke, so that when the sleeve does reach its lowermost position, downward movement of the hammer is already well under way.

It is pointed out that as soon as the piston has withdrawn from the control sleeve the pressure acting upon the sleeve is relieved and the latter is returned to its upper position by the spring 41. As the hammer is returned to its upper position by the spring 22 following the striking of the blow, the control piston is moved into the control sleeve and the latter immediately is moved downwardly by the pressure of the drilling fluid so that a second cycle is commenced. The design and proportions of the various elements of the tool control, to some extent, the frequency of the impact cycles. Several hundred blows per minute upon the anvil 73 may be obtained, and due to the considerable mass of the hammer, these blows are of large force and power.

It is also pointed out, that as the hammer moves upwardly, the drilling fluid exerts an increasing pressure upon the control sleeve whereby the sleeve may start its downward stroke or travel before the piston and hammer reach their uppermost position. Thus, at this moment the sleeve and the piston would be moving in opposite directions. This function is dependent upon the design and proportions of the various elements, but in any event, the sleeve would start its downward travel as soon as the piston enters the bore 52.

In drilling operations, the drilling string may be rotated at the same time that mud is being pumped downwardly through the string, so that the bit 78 is rotated over the surface being drilled, and at the same time, several hundred blows of considerable magnitude are delivered each minute through the lower cutting edges of the bit to the formation. In this manner, very fast and efficient drilling of extremely hard formations is obtained while preserving the other desirable characteristics of rotary drilling.

It is to be noted, that the flow of drilling fluid through the port 80 of the bit 78, is never interrupted but a continuous lubricating and flushing action is maintained. This worth-while result is obtained by reason of the structure of the piston and control sleeve. As soon as the piston enters or nears the control sleeve on its upward travel, communication through the bore 52 of the control sleeve is reduced or minimized; but, the sleeve immediately begins to move downwardly, thereby displacing drilling fluid therebelow. And, as the sleeve nears or reaches the lower end of its stroke, the hammer is moved downwardly displacing additional fluid. This action is very rapid, and by this means fluid continues to move downwardly at all times during the cycle. The frequency of the

cycles is sufficiently high to insure very little pulsation of the drilling fluid.

In my earlier invention, as set forth in my co-pending application, Serial No. 686,497, filed July 26, 1946, the hammer was adapted to be returned to its upper position by means of a compression type spring which encircled a portion of the hammer. Being of a compression style, this spring is subject to columnar stresses and tends to wear and abrade to some extent due to its position in between the hammer and the inner wall of the housing. In the present invention, this problem is overcome through the utilization of the tension-type spring at resilient type 22. This spring remains at all times under a certain minimum degree of tension, or, in other words, a certain minimum tensile stress is constantly applied to said spring. This stress reaches a substantial minimum when the hammer is at the uppermost point of its travel, and reaches a substantial maximum immediately before the hammer strikes the anvil 73. Being thus under a constant tensile stress, the spring 22 retains a straight line position between the eye bolt 20 and the upper end of the cable 53. It is not subjected to columnar stresses and does not tend to bow under the applied load and thus abrade against the inner surface of the housing section 14. At the same time, the employment of the flexible cable 53 compensates for minor misalignments of the various elements and aids in guiding the piston 56 into the bore 52 of the control sleeve 35.

This same desirable result may be achieved with respect to the control sleeve spring 41 which may be replaced by tension-type springs as illustrated in Figs. 10 through 16 of the drawings in the modification of this invention. The structure employed for this modified form of the invention is substantially identical in most respects to that previously described, and only those portions which are altered have been illustrated.

In this modification, the upper section 10 is replaced by a nipple 82 having an upstanding screw-threaded pin 83 which engages the lower end of the tubing string (not shown). The next lower section 84 of the housing is extended upwardly and screw-threadedly connected to the lower end of the nipple 82 at 85. The axial bore 86 of the section 84 is reduced in diameter near the upper end of the section so as to form an internal, annular, boss 87 having a counter-bore 88 in vertical alinement with the bore 86. A pair of diametrically opposed longitudinal grooves 89 are cut in the wall of the bore 88 and extend downwardly from the upper end of the boss 87 to a point near the central portion thereof. A transverse supporting plate 90 engages within the groove 89 and carries a depending eye rod 91 which may be welded or otherwise suitably secured to said plate. The upper end of the hammer spring or tension-exerting element 22 is received within the eye 91 and supported thereby, and the upper end of the cable 53 is suitably connected to the lower end of said spring. The cable extends downwardly through the balance of this modification of the tool and is secured to the control piston 46 in the same manner as previously described.

The lower end of the section 84 is connected by a screw-threaded joint 92 to the upper end of the next lower housing section 93. The section 93 is formed with an internal annular shoulder 94 near its upper end, said shoulder receiving an annular supporting ring 95 which has a snug sliding fit within the bore of the upper por-

tion of said section 93. The ring is provided at its lower end with an inwardly extending annular flange 96 which carries a plurality of downwardly extending supporting bolts or pins 97. 5 A suitable coiled, tension-type, spring 98 is secured to the lower end of each of the pins 97, and the lower ends of the springs 98 are in turn secured to the upper ends of a plurality of supporting pins 99 projecting upwardly from the flanged upper end 100 of a control sleeve 101. The control sleeve has a sliding fit within the bore 102 of a nipple 103 secured to the lower end of the housing section 93 and has its lower end projecting below the lower end of said nipple. The upper end of the housing section 42 is secured to the lower end of the nipple 103, and the balance of the tool from this point downward is the same as that previously described.

A suitable resilient packing ring 104, which may 20 be formed of synthetic rubber or any other suitable material, is partially recessed within the outer periphery of the control sleeve adjacent the lower end thereof, the ring 104 being greater in thickness than the depth of the recess 105 in 25 which it is positioned so as to project radially outwardly from all sides of the control sleeve. The ring is adapted to engage within an annular box 106 cut into the lower end of the nipple 103 so as to surround the control sleeve, such engagement taking place when the sleeve moves upwardly within the bore 102. The side wall of 30 the box 106 is tapered or inclined so that as the ring 104 moves into the box, it encounters increasingly restricted clearance. For this reason, the ring and the box function as a dash-pot when 35 the control sleeve moves upwardly, and the ring 104 operates as a gently-acting stop ring to limit the upward travel of the control sleeve. The ring may at times engage the bottom or upper end of 40 the box 106 and in such instances operates as a positive stop. However, because of the fluid always present within the box and the balance of the tool, the stopping action of the ring comes 45 into existence with some degree of slowness as the ring, in moving upwardly with the control sleeve, moves into the progressively restricted box 106.

The control sleeve is limited in its downward travel by the engagement of its flanged upper end 100 with the upper end of the nipple 103, so that 50 when the tool is set in operation, a positive limit of downward travel for the control sleeve is provided. A dash-potting action is also achieved in accomplishing this stopping function since the upper end of the nipple 103 is counter-bored to 55 form a shoulder 107 upon which the flange 100 seats. The side wall 108 of the counter-bore is flared outwardly so that, as the flange 100 moves downwardly, it encounters increasing resistance to the displacement of the fluid present between it and the shoulder 107. In this manner, the control sleeve is prevented from seating with destructive force and velocity upon the shoulder 107, and is caused to engage said shoulder in a somewhat more gentle fashion and with the absence of any mechanical damage.

The utilization of the tension type springs 98 in place of the compression type spring 41 results in the same advantages and improvements as the replacement of the coiled type compression spring for the hammer 42 with the tension type spring 22. The columnar stresses to which the spring 41 is subjected are eliminated, and the resultant wear upon the spring means for support of the control sleeve is eliminated. In addition, by the utilization of a plurality of springs

11

rather than a single spring, mechanical failure is rendered less serious since the percussion tool may continue to operate even though one of the springs 98 has given way.

It is not deemed necessary to provide a detailed description of the operation of this modification of the invention since the functions of the various elements remains substantially the same as previously described. The major differences between the first and second forms of the invention reside in the replacement of the compression type spring 41 with the tension type springs 98, and the modified structure of the control sleeve and its support for affording dash-pot action in both directions of movement of said sleeve.

This invention also contemplates an improved method of drilling wells, and in particular, oil wells wherein deep holes of sizable diameter must be forced through earth formations of varying degrees of hardness and difficulty of drilling. Heretofore, roller type bits have implemented the most successful method of drilling, such method involving rotation of the bit while applying a constant or very slowly changing load or pressure upon said bit.

As previously pointed out, it is preferable to employ a roller type bit with the percussion tools set forth herein, such preference arising from the new method of drilling which ensues. By mounting a roller bit of the type normally employed for drilling hard formations upon the present percussion tool or any other suitable tool capable of delivering a series of impact blows while rotating the bit, extremely efficient drilling is obtained. Therefore, this new method broadly encompasses the combination with a percussion tool of a roller bit with the steps of rotating such a bit while delivering impact blows thereto forming the essential portions of the method. Greatly increased drilling speeds have been realized through the utilization of this method in practical field tests carried out in wells being drilled. Substantially all of the advantages of a roller type bit are retained, while the additional advantages of the percussion tool are added so that the formation is chipped, crushed and broken while at the same time being cut and ground through the rotating of the roller bit.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A well percussion tool which comprises a tubular housing, an inlet for the supply of mud fluid to said housing, a mud outlet from said housing, two elements in said housing mounted for axial reciprocation relative thereto, one of said elements having the form of a sleeve fitting slidably in an opening formed by a radially

12

inwardly extending portion of said housing, said portion having an annular recess therein around said sleeve with the wall of said recess tapering toward the sleeve, an outwardly radial circum-

ferential projection from said sleeve of such size as to substantially fill the narrowest portion of said recess when moved thereinto by said sleeve to thereby coat with the sloping wall of said recess and effect a dash-pot action therewith to limit the movement of said sleeve, the other of said elements having the form of a piston fitting slidably in said sleeve, said two elements forming a valve to control the flow of mud through said housing from said mud inlet to its outlet, a hammer attached to said piston for reciprocation therewith, a first elastic means for urging said sleeve upwardly, a second elastic means including a coil spring secured to the housing above said sleeve, a cable connecting said piston to said spring, said spring acting in tension to return said piston to its initial position in engagement with said slideable sleeve after said hammer has been forced downwardly in said housing.

2. The tool of claim 1 wherein said portion has a second annular recess therein facing oppositely from first said annular recess, the wall of said second recess also sloping inwardly toward said sleeve, a second outwardly radial circumferential extension from said sleeve of such size as to substantially fill the narrowest portion of said second recess when moved thereinto by said sleeve to thereby coat with the sloping wall of said second recess and effect a dash-pot action therewith and to limit the extent of movement of said sleeve in a direction opposite to that in which it is limited by first said projection and recess.

3. The tool of claim 2 wherein said first elastic means is a coil spring connected to said housing and said sleeve and acting in tension to move said sleeve upwardly.

ROSS BASSINGER.
